UNITED STATES PATENT OFFICE.

HENRY B. LYTLE AND JOHN J. CARTY, OF BOSTON, MASSACHUSETTS.

METHOD OF AND APPARATUS FOR INDIVIDUALIZING TELEPHONE TIME-SIGNALS.

SPECIFICATION forming part of Letters Patent No. 299,561, dated June 3, 1884.

Application filed January 10, 1884. (No model.)

To all whom it may concern:

Be it known that we, HENRY B. LYTLE and JOHN J. CARTY, of Boston, in the county of Suffolk and State of Massachusetts, have 5 invented certain Improvements in Telephone Time-Signal Distribution, of which the following is a specification.

Our invention relates to the distribution of standard time by means of the well-known 10 telephone - exchange system of subscribers' wires and apparatus; and it consists more particularly in a method of individualizing the distributed time-signals in such a way that they may be supplied to such subscribers and 15 over such subscribers' lines as may be found desirable, while they may be rigidly excluded from lines that are not to be supplied.

It consists, further, in certain specific instrumentalities and circuit arrangements in 20 which the said method may be embodied and through which the desired result may be effectuated.

In Letters Patent No. 287,710, issued October 30, 1883, to John M. Oram, a method and 25 apparatus are described, by which all of the subscribers of a telephonic system are furnished with correct time from a single standard clock by continuous signals repeated throughout all the minutes of the day. The 30 method consists in interposing a battery and circuit-breaker in the common ground-wire of all the circuits of a telephone-exchange, and in causing a clock, by means of suitable intervening mechanism, to operate the said circuit-breaker closer in such a way that the hour and the exact number of minutes thereafter are successively repeated upon the circuit every minute of the day, and thus any subscriber on any wire desiring to be acquainted with the correct 40 time to the minute has only to take his telephone from its support and put it to his ear, when he will distinctly hear first the hour, and immediately thereafter the minutes after the hour. In practice, however, it has been 45 ascertained that in many cases it is desirable to extend the facilities for the distribution of the time to a certain number only of the subscribers over their individual lines, and equally undesirable to extend the same facilities to 50 others, and, for reasons which hereinafter ap-

pear, how to accomplish this has proved very problematical. It is usual to charge a small rental to subscribers receiving the time-signals regularly, and as many of the subscribers have no need of the time as corrected, and therefore do not care to pay any rental therefor, it is essential that an effectual plan should be devised whereby those not paying shall not receive the time. It would seem at first as though the problem of excluding the said time-signals from a portion of the subscribers' lines would be easily accomplished by simply connecting the said lines to a separate and independent ground-wire not acted upon by the clock and circuit-breaker; but by reason of the extreme sensitiveness of the telephone as a receiving-instrument and the intensity of induction between parallel lines such is not the case.

It has been demonstrated by experience that 70 if a definite number of lines are furnished with the time by the clock and circuit-breaker nearly every line radiating from the same central office will be the recipient of similar signals by induction, and this is especially the 75 case in the more recent methods of construction, wherein the radiating lines are, for the first half-mile or so from the central station, conducted, for economy of space, through aerial cables, in which a number of lines are massed close together in a small space. It has also been demonstrated by experience that by our invention the time-signals may be readily confined to the desired lines; and to this end our invention consists, first, in sending induced 80 currents of a rhythm and number equal to the beats of the circuit-breaker and corresponding to the time at any given minute over the lines to be supplied; secondly, in sending simultaneously a confusing signal over the lines 85 which are not to be supplied; and, thirdly, in using separate ground-wires and switch-terminals, whereby every possible means for separating the two series of lines from one another are employed.

Our improvement is based upon the herein-before-cited patent of Oram, which, so far as we know, represents, prior to our invention, the state of the art, and to which reference may be made. Since the general plan of dis- 90

tributing the time has not been departed from in our invention, we do not regard it as necessary to rehearse it here, the changes and modifications which are essential being entirely in the arrangement of the central-station apparatus and circuits, as we shall now describe.

Figure 1 of the drawings represents, diagrammatically, a series of the lines which are arranged to receive the time-signals. Fig. 2 is a similar diagram of the lines which are arranged in such a manner as not to receive the time-signals, but, in contradistinction thereto, to receive a confusing signal. Fig. 3 illustrates the mechanism by which the time-signals are transmitted to one series and the confusing signal simultaneously to the other series of lines. Fig. 4 is an elevation of the special form of the annunciator shown in Fig. 1. Fig. 5 is a diagram exemplifying a modification of the method of transmitting the time-signals. Fig. 6 shows the arrangement of the two series of lines upon a central-station switchboard; and Fig. 7 shows the central-station annunciator provided with a polarized armature, whereby, when currents sufficiently strong to ring the subscriber's bell are sent to line, the annunciator is prevented from being acted upon.

Referring, first, to Figs. 1 and 4, which are to be considered together, the main lines L are shown as each uniting its own sub-station s with the central station, S, where a number of lines center. Arriving at the said central station, each line is connected with the helices $m m'$ of its own annunciator A, and from thence, by wire 1, to the common ground-wire, g, and ground G. The annunciator is shown in elevation by Fig. 4, and consists of a double electro-magnet mounted on a base, b. The entire spool of one leg of the magnet, together with the half-spool m' of the other leg, is included in the line-circuit. The lower helix or spool of the rear leg of the magnet is entirely insulated from the line-circuit, and is adapted to be included in and to form part of a separate and local circuit. The annunciator, as usual, is furnished with an armature, a, and a drop signal or tag, t, pivoted at p to the base b, and normally upheld by the engagement of the catch e at the front end of the armature with a notch or slit in its upper end, in a manner well understood. Under certain contingencies, to be hereinafter enumerated, the armature a will be preferably polarized, so as to respond only when the currents of a certain polarity traverse the coils m, and so as to remain inert when the coil m' only is energized.

It will be understood that the office of the helices $m m'$ is to energize the annunciator by means of currents received from the sub-stations, and thus to actuate the drop and produce a call-signal. On the contrary, the office of the helix h is to change the magnetic condition of the core of the electro-magnet, and thus by induction to generate magneto-elec-

tric currents in the main-line helices $m m'$, and consequently in the main line itself, these induced currents corresponding in time and duration with a clock-operated circuit-breaker, and actuating the receiving device at the sub-station to repeat the time-signal.

The auxiliary or local helices h of any desired number of circuits—i. e., those which are to be supplied with the time-signals—are included serially, as shown in the drawings, in the local circuit of the battery B. A circuit-closer, C, holds this local circuit normally open; but a controlling wheel or roller, R, provided with the requisite number of spur-teeth, is adapted to rotate, making a complete rotation between each minute and the next, and as each of the projecting teeth touches the spring c it depresses the said spring on the lower spring, c', and momentarily closes the circuit. The circuit of the battery B may be traced as follows: from B by wire 4 to helix h of the first annunciator, then by wire 5 to the next, 6, to the third, and so on through all of the helices h , after which it continues by wire 7 to one side of the circuit-closer C, then by the opposing spring c' and wire 8 to the other pole of the battery.

It will be observed that although we have shown and described the circuit-closer as holding the local circuit normally open, and closing it to effect the necessary magnetic changes, we may readily reverse this condition and maintain the circuit normally closed, effecting the necessary changes by opening it in correspondence with the spur-teeth i of the rotating cylinder R. We prefer, however, the open-circuit form shown.

We propose to employ substantially the same devices for changing the time-signal in accordance with the ever-changing time of the several minutes and hours as that employed in the Oram patent, which we have hereinbefore referred to, and a portion of this device is the rotating cylinder, shown in Figs. 1 and 2 as the actuating device of the circuit-closers. It is fitted with spur-teeth or studs i in a manner resembling the arrangement of a music-box. As shown in Fig. 3, the local circuit has in practice three circuit-closers, C, to which the respective main wires 7 and 8 of the local circuit are branched. The wire 7 is united to the upper spring of the circuit-closers by the branch wires 10, and the wire 8 is similarly united to the lower spring by the wires 11. To operate these circuit-closers there are three sets of studs, i, on the rotating cylinder—viz., one set representing the hours, and these in Fig. 3 are supposed to have already passed the left-hand circuit-closer, a second set representing the tens of the minutes, and these are shown as being in the act of passing the middle circuit-closer, only two or more teeth having now to pass, and a third set representing the units of minutes, which have not in the drawing yet reached the third circuit-closer.

It is obvious that, since the local circuit is

normally open at all three circuit-closers, when the teeth or projecting studs *i* of the cylinder press down the spring *c* of any one of them, the circuit is closed for an instant until the 5 stud releases the spring and passes onward. The operation of these devices may be briefly indicated: When the circuit-closers are open, the annunciators *A* are inert. When the said circuit-closers have their springs *c* and *c'* brought together by the impingement of the cylinder-studs *i*, corresponding to the hour and minute of the day, the circuit of the battery *B* is closed, and the current flows round the coils of the helix *h*, magnetizing the core and 10 producing an induced current in the main-line coil *m m'*. This passing over the line repeats the signal upon the telephone or other receiving-instrument when the said instrument is brought into the circuit. The signals sent of 15 course correspond in number to the number of times the local circuit is closed at *C*. Ordinarily the induced current is strong enough only to repeat the signals to the subscriber by means of his telephone; but if it is desired 20 that the signal shall be repeated on the bell *D* of the said subscriber, it is only necessary to increase the strength of the battery *B*. If, however, the induced current is thus made strong enough to repeat the signal upon the 25 bell *D*, it is found also to be sufficiently strong to drop the annunciator-signal, which should respond only to the call of the subscriber. We avoid this by polarizing the armature *a* of the 30 annunciator, as shown in Fig. 7, and by connecting the battery *B* so that its current will 35 flow around the core of the annunciator, through the helix *h*, in such a direction as to produce magnetism in the said core and in the pole thereof of like polarity to that of the free 40 end of the armature. The core then, instead of exerting an attractive power upon the armature, will repel it, and the drop-signal will not be actuated, while it is left perfectly free to respond to the alternating currents of the 45 subscriber's call.

We will now, referring to Figs. 2 and 3, describe the arrangement of the lines leading to such subscribers' stations as are not to be supplied with the time-signals. The several lines *L* are fitted with bells *D* and telephones *T*, as usual, and, as in the former series, unite the sub-stations *s* with the central station *S*. The annunciators *A* are of the ordinary pattern, and are not provided 50 with the extra and auxiliary helix *h* or with the local circuit and battery. The several line-circuits each proceed from the sub-station ground *G* through the bell *D* and telephone *T* to the line *L*. Arriving at the central station, 55 the circuit is continued through the annunciator-wire 3, common to the series. This connects, through battery *B'*, wire 12, circuit-closer *C'*, and wire *g*, to ground at *G*. It is immaterial whether the battery *B'* be placed in the 60 circuit at the point shown or whether it is included in the wire *g* between the circuit-closer

C and the ground. The annunciator *A* in this case serves merely as an instrument to indicate the call of the subscriber, and is, as usual, provided with armature *a* and drop-signal *t*, 7c controlled by the catch *e* at the end of the armature. The rotating disk *R* is affixed to the same axis as the cylinder *R*, and it may be a part thereof; or it may be, as shown in Fig. 3, a separate disk fastened upon the axis and 75 insulated therefrom. It is by no means necessary that the rotating disk *R* shall be upon the cylinder-axis *J*; but I prefer so to place it for convenience of operation. The several spur-teeth or studs, *i*, arranged round the periphery of the disk, may be continuous, as shown, and adapted to actuate the circuit-closer continuously; or they may be attached only to a portion of the periphery corresponding in extent to the total extent over which the 80 time-signal studs are arranged on the other portion of the rotating cylinder, so as to operate the circuit-closer only during the exact time that the time-signals are being sent. By the impingement of the studs *i* upon the projecting portion of the spring *k'*, the said spring is caused to alternately break and close the circuit by its alternate connection and disconnection with the upper contact-point, *k*. Like the local circuit-closer *C*, the main circuit-closer *C'* may be reversed without impairing 95 its effectiveness—that is, it may in its normal condition be open, instead of closed; and this change may, when required, readily be made by any one skilled in the art.

The arrangement we have herein shown and described constitutes the means whereby the confusion-signal is sent over the lines which are not to be supplied with the time; and it may now be seen that our plan, in general, for 100 selecting certain lines for time-service and excluding other lines from the benefits thereof is to remove the ground-wire leakage and reduce the induction from wires conveying time-signals by preventing the ground-wire from 105 being a factor in the case, and by originating the signals by means of an induced current, and, further, by sending simultaneously upon lines which are not to be served a confusing or obliterating signal, which will prevent any 110 approximation to the time-signal from being heard.

We show in Fig. 5 a modified arrangement for time-signaling, which in some instances may be substituted for that shown in Fig. 1, 115 and which operates by weak currents. The battery *B*³ is normally connected with the line *L* through the annunciator *A*; but it must be of such a degree of strength that it will not magnetize the magnet-cores to such an extent 120 as to attract the armature and drop the signal. The clock *E* alternately closes and opens the local circuit, including a battery, *B'*, and electro-magnet *W*, and this magnet, either directly or through the intervention of the rotating cylinder shown in Fig. 3, alternately 125 breaks and closes a short-circuit round the 130

main battery B^3 via armature-lever w , wire 14 wire 13, and contact-screw z , producing electrical variations upon the line, and thus giving the time-signals to the sub-stations.

5. In addition to the foregoing devices, we have found it advisable to provide separate ground-wires for the two series of wires. This arrangement is shown in Fig. 6. The lines L are all at the central station led to the switch-board H . After passing the said switch-board, such of the lines as are to be supplied with time—the three, for example, on the left—may be terminated upon the cross-bar o , which, by the wire v , battery B^3 , and wire g , is connected with the ground, the battery, as in Fig. 5, being controlled by a clock, E , magnet W , and the shunt-circuit 13 and 14. The lines which are not to be supplied are connected with the lower cross-bar, q , and thence by wire g' , 20 through the circuit-closer C' , to a ground terminal at a place distant from the first.

We do not confine ourselves to the exact and precise instrumentalities herein shown, since it is evident that the principle which 25 forms the essence of our invention may be varied greatly without being departed from, and that it is not dependent upon any particular form of apparatus. We may, for example, instead of attaching to the annunciations auxiliary helices included in a local circuit and energized by a current varied in correspondence with the time-signals, use a reel, upon which the primary or energizing circuit is wound in one or more layers, and, interposing 35 in the circuit of each a length of fine insulated wire, wind the said lengths of fine wire together upon the said reel over the primary wire. In the employment of this device a core of iron would ordinarily not be essential, 40 unless very strong currents are desired.

Having now described our invention, we claim—

1. The hereinbefore-described method of regulating or individualizing the supply of 45 time-signals to the subscribers of a telephone-exchange system by producing induced currents corresponding to the time-signals in the line-circuits to be supplied, and simultaneously sending a confusing signal or succession 50 of signals over the line-circuits which are not to be supplied.

2. The method herein described of compensating for the involuntary distribution of time-signals by induction and leakage over telephone-circuits which are not intended to receive the same, which consists in transmitting over the said circuits a confusing or obliterating signal, whereby the induced time-signals are confused and made incomprehensible. 55

6c 3. The method hereinbefore described of producing induced currents corresponding to time-signals in a series of telephone line-circuits, which consists in passing battery-currents equal in number and duration to the said 65 time-signals through a series of helices (one for each line) placed on the core of the annun-

ciators of the said telephone line-circuits, and in juxtaposition to the helices thereof, substantially as specified.

4. The combination, in a telephone-exchange 70 system, of a series of main lines and central-station annunciations therefor, the said annunciations each being provided with an extra helix, a local battery-circuit including the said helices, and a circuit-closer for said local circuit adapted to be operated by a clock-actuated time-cylinder, and to send time-signals to line, with a second series of main lines and a battery and circuit-closer in the main ground-wire thereof, the said circuit-closer being 80 adapted to alternately make and break the circuit of the said battery and ground-wire during the time of transmission of time-signals over the first series of lines, for the purposes specified. 85

5. In a telephone-exchange, a time-transmitting system therefor, consisting of the combination of a series of main lines, receiving-instruments at the respective sub-stations of the said main lines, an annunciator for each line at the 90 central station, an auxiliary helix placed on each of the said annunciations, a local battery, a local circuit including the battery and the said auxiliary helices, and a circuit-closer actuated by a rotating cylinder and arranged to 95 close the circuit under the influence of the said cylinder a number of times corresponding to the hour and minute, whereby currents of similar number and character may be induced in the main lines and the time-signals 100 reproduced in the receiving-instruments thereof, substantially as described.

6. The combination, substantially as described, with a main telephone-line and a sub-station bell included therein, of the hereinbefore-described time-transmitting devices, consisting of the local battery, circuit-closer, time-repeating cylinder, auxiliary annunciator-helix, and the annunciator, provided, as described, with a polarized armature, whereby 105 when the actuating current is strong enough to ring the bell it is prevented from giving the annunciator-signal.

7. The combination, in an electric annunciator, of an electro-magnet provided with two 115 separate helices, the larger of the said helices being adapted for inclusion in the main line, and the smaller in a local circuit, and a polarized armature therefor adapted to respond to the magnetism of the electro-magnet when induced by the main-line helix, but not when induced by the local circuit, as described. 120

8. The combination, with a series of telephone-lines, of a series of local circuits arranged in inductive proximity to a portion of 125 said main lines, and adapted to generate induced currents therein, a series of local circuit-closers adapted to open and close the said local circuits, a separate circuit-closer included in the common ground-wire of the remaining portion of the series of main lines, and a revolving clock-controlled cylinder act- 130

uating the said circuit-closers, and adapted to close the local circuit-closers in correspondence with time-signals, and simultaneously open and close the main-line circuit-closer 5 without reference to time, for the purposes specified.

9. In combination with a series of telephone-lines and time-transmitting signaling apparatus for a portion of the said lines, means, 10 substantially as described, for sending a confusing signal over the remainder of the said telephone-lines, for the purpose specified.

In testimony whereof we have signed our names to this specification, in the presence of two subscribing witnesses, this 31st day of December, 1883.

HENRY B. LYTLE.
